(57) **CLAIM**

The ornamental design for a ceiling fan, as shown and described.

DESCRIPTION

FIG. 1 is a perspective view of a ceiling fan showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is bottom plan view thereof; and,

FIG. 9 is an enlarged detail view of area 9 circumscribed in FIG. 1.

The broken lines depict portions of the ceiling fan that form no part of the claim.

The long-dash short-dash broken lines denote the boundaries of the area of the detail and form no part of the claimed design.

1 Claim, 9 Drawing Sheets
